(57) **CLAIM**

The ornamental design for hardhat lip speaker or mike mount, as shown and described.

DESCRIPTION

FIG. 1 is a front and left isometric view of a hardhat lip speaker or mike mount showing our new design, the broken line showing of the hardhat lip and speaker is for illustrative purposes only and forms no part of the claimed design; FIG. 2 is a front elevation view of the mount.

FIG. 3 is a left side view thereof.

FIG. 4 is a right side view thereof.

FIG. 5 is a rear view thereof.

FIG. 6 is a top view thereof; and,

FIG. 7 is a bottom view thereof.
